UNITED STATES PATENT OFFICE.

JOHN EDWARD JENNINGS, OF BROOKLYN, NEW YORK, ASSIGNOR, BY MESNE ASSIGNMENTS, TO MILLIKEN BROTHERS MFG. CO., INC., A CORPORATION OF NEW YORK.

BUILDING CONSTRUCTION.

1,342,021.

Specification of Letters Patent.

Patented June 1, 1920.

Application filed March 28, 1916. Serial No. 87,153.

To all whom it may concern:

Be it known that I, JOHN EDWARD JENNINGS, a citizen of the United States, and a resident of the borough of Brooklyn, county 5 of Kings, city and State of New York, have invented certain new and useful Improvements in Building Construction, of which the following is a specification.

The improvements relate to buildings and 10 other structures and are particularly designed for use in connection with what is known as "shed construction," which includes the construction of roofs for various structures, store houses, temporary dwellings, 15 and shelters, garages, hangars, work-shops, and other buildings, but their use is not limited to these and may be employed in various other structures. They are also primarily designed to be embodied in structures 20 having relatively light metal parts.

The objects of the improvements are, among others, to provide a frame which may be manufactured in individual units at a shop or factory, where materials and fabricating equipment are convenient, and assembled in structures of various form and size consisting substantially of multiples of said units, without material alteration or the employment of skilled labor or non-portable tools and machinery; to effect a saving 30 in time and labor in connection therewith and reduce the cost and inconvenience of transportation; and also to so arrange the parts that the structure may be readily 35 altered or enlarged or taken down and the parts reassembled in the same or a different form, if desired. There are also other objects and advantages which will appear to those skilled in the art.

40 By the use of the improvements a large stock of the necessary structural units or parts may be made up, and these parts used as required for buildings of different sizes and for different purposes.

45 The improvements are illustrated in the accompanying drawings referred to herein, in which Figure 1 is a schematic illustration of sections of buildings embodying the said improvements.

50 Fig. 2 is a side elevation of a half span of a roof truss and a supporting column embodying the same.

Fig. 3 shows a construction in which the

units are used on an earth base instead of a concrete base as in Fig. 2.

Fig. 4 is an elevation of the ventilating ridge construction of a roof.

Fig. 5 is an elevation of a detached structural unit.

In carrying out the improvements a number of frames of identical form and construction are employed, and the frame of the building or other structure is formed of a plurality of these units placed together in various positions and connected by rivets, 60 screw-bolts or other suitable fastenings. These units, in the embodiment of the invention illustrated, consist of frames in the form of right-angled triangles with an auxiliary member extending from the right 65 angle to the hypotenuse intermediate its ends, the joints of the triangle in each case being made by plates formed and positioned so as to connect the members of the triangular frame and also serve to connect them 70 with other units and structural elements.

The vertical member A of each triangular unit is connected with the bottom chord member B by means of the gusset-plate C and with the top chord or hypotenuse member D by means of the heel-plate E, and the extremities of the two chords are connected by the toe-plate F, the said member and chords, in the present instance, being angle 85 bars. In each instance the plates are provided with rivet holes to receive suitable fastening members passed through the angle bars near their extremities and through the plate. The stay G is secured to the plate C in similar manner and to the top chord angle 90 D by having a rivet or other fastening passed through the two parts at their intersection.

The gusset-plate C extends below the bottom chord member B and is provided with 95 rivet holes to receive the fastenings passing through the ends of the tie members H, so that each tie member connects two of the said plates. The toe of each triangular unit is secured to the heel of the abutting unit by 100 means of an angle I riveted or otherwise secured to the depending portion of its toe-plate and to one web of the adjacent vertical member, or, by means of a common eave-plate J, to the toe of the post or column 105 formed of another triangular unit placed in

an upright position to form the said column or upright of the structure.

At the ridge of the roof the units are united by riveting or otherwise securing the 5 abutting vertical members together and supplementing this by a plate K uniting the plates C and an angular ridge tie L uniting the plates E. The connecting parts K and L are provided with rivet holes which register with the rivet holes of the plates C and E respectively, so that fastening means may be passed through the said members and the plates.

When the posts are set in the earth an 15 extension frame consisting of the batter-post M, vertical post N and base member O united at their extremities and reinforced by the diagonal stay P may be used, the upper ends of the two posts M and N being 20 connected with the plates E and C respectively. This supplemental frame however, is not necessary in all cases, and the bottom of the vertically disposed unit may be set in the earth if desired.

25 When the posts are set in concrete the post M with a clip S secured to its lower end, and a hook member R may be used and embedded in the concrete to anchor the said post, but in this case also the base of the 30 upright unit may be embedded.

The construction of a full roof span with 35 supporting columns has now been described. As illustrated in Fig. 1 the roof truss may consist of two or more units, according to the length of the span desired, and the columns may be one or more units in height, and in the latter instance a plurality of units vertically disposed and joined together may form the base and a single unit mounted 40 thereon the top of said column. A stay T serves to reinforce the units when used in a column against strains tending to spread or bulge them and such a stay may be made a part of each of the units if desired to give 45 additional strength and so that it will not be necessary to select particular units for use in this manner.

Assuming that the base chord of each unit is twelve feet in length and the vertical 50 member four and a half feet, so that the hypotenuse is approximately thirteen feet, the height of the columns will be multiples of twelve and the width of the span multiples of twenty-four feet. In the illustration of 55 Fig. 1 are shown methods of assembling the units to form frames with walls twenty-four feet in height and trusses composed of two, four or six units or with walls twelve feet in height and the same units in the roof 60 span. It is obvious, however, that various other combinations may be made. It is also apparent that the elements, without change, may be so combined as to form frames of various other desired forms to meet the requirements of use.

The system of construction herein described may be employed for structures widely varying in area and in form, and when desired the frame-work thus formed may be reinforced by suitable tie rods or the like passed through holes U punched in the members and extending from one frame to another. It will also be understood that these frames are adapted to be connected by rods, bars or other members secured to a 75 plurality of them and bracing them against movement with respect to one another. As such parts are not necessarily of peculiar construction and are commonly used in connection with frames formed by other 80 methods it will not be necessary to illustrate or to describe them further. A method of applying roof and wall sheathing, however, has been shown. This consists of the use of purlins V, running at right angles 85 to the frames formed in the manner heretofore described, and secured thereto by means of angle ties V', and overlapping sheets of corrugated or other metal W supported thereon. These purlins may be of channel 90 iron or other form or of wood, and serve to unite the individual multiple unit frames and also to support the roof and sides of the structure.

The ridge unit (see Fig. 4) is secured to 95 the purlins V by means of the plates X riveted or otherwise secured to the said purlins and also to the posts Y supporting the cap Z by means of the angle Y' riveted to the said posts and to the cap. By the use 100 of this member the ridge may be covered, and may be closed if desired. But if it is desired to provide for ventilation at this point it is only necessary to remove the bolts connecting the plates X with the posts Y and 105 to move them up until the bolts can be passed through the holes lower down. As the cap-plate Z extends longitudinally of the ridge, in ordinary cases it will be necessary to force the said cap up at one or two 110 points at a time, but the flexibility of the cap will permit of this especially when the bolts securing it on the ridge are removed at two or more adjacent sections before it is raised at one section.

The use of the structural units herein described and shown is not limited to any particular part of the building, but may be employed in many other ways and in the formation of many other structures than those 120 shown in the drawings, and it is one of the great advantages of the multiple unit system of the present improvements that it is adaptable to various uses and various structures. For instance while rods and ties of 125 common form may be employed to connect frames constructed of the units, and have been referred to herein, the units themselves may be used for that purpose without material change, and while the shed construction 130

illustrated in the drawings is of plain and simple form, it may be supplemented by cupolas, bows, or other architectural embellishments, and these parts formed of the 5 same structural units.

What I claim is:

1. A building-structure including a plurality of aggregated interchangeable structural units, each essentially comprising a 10 long component to form a base-member, a relatively shorter component to form a side-member, and a third component of greater length than either of the other two components to form a hypotenuse-member, these 15 three components being joined to present a perimeter involving only a single right angle and two acute angles, and member-attaching elements for holding said components permanently assembled and, also for connecting 20 one unit with other units so that the hypotenuse-components of a series of units are all alined to form a straight, continuous and unbroken roof-supporting surface.
2. A building-structure including a plurality 25 of fabricated interchangeable structural units of identical form, each essentially comprising a long component to form a base-member, a relatively shorter component to form a side-member, and a third component of greater length than either of the other two components to form a hypotenuse-member, these three components being 30 permanently joined together to form a perimeter composed of a single right angle and two acute angles, and member-attaching elements for connecting said components together and constituting permanent means on each unit for securing a series of 35 units to each other so that the hypotenuse-components of the series are all alined to form an approximately straight, continuous and unbroken roof-supporting surface, the base-members of the several units being all 40 unalined, non-coincident, and in substantially parallel relation.
3. A building-structure including a plurality 45 of fabricated interchangeable structural units of identical form and dimensions, each essentially comprising a long component, a relatively shorter component, and a third component of a greater length than either of the two components and connected thereto to form a hypotenuse-member, these three components being joined to 50 form a right-angled triangle having a perimeter consisting of a single right angle and two acute angles, and member-attaching elements disposed at each of said three angles to hold the components as a permanent assemblage and uniting a series of the units with only their respective acute angles joined and with the hypotenuse-members of the series of units all alined to form a 55 continuous and unbroken supporting surface, the base-members of the several units 60
- being all unalined and non-coincident but some disposed in substantially parallel relation to each other and some in substantially right angular relation to one another, and unit-tying members connected to a plurality of the units and substantially paralleling the hypotenuse-members thereof and forming with the adjacent long and short members a right-angled triangle. 70
4. A building structure including a series 75 of fabricated structural triangular units of identical form, each complete in itself and adapted to be assembled as a roof-supporting series and capable, then, of being disassembled as individual, self-contained units; 80 each of said units comprising a long component to form a base-member, a shorter component to form a side-member, and a component of greater length than the base-member to form a hypotenuse-member, the 85 three components being joined to form a right angled triangle having a perimeter comprising a right angle and two acute angles; the series of joined units having their respective acute angles juxtaposed so 90 that the hypotenuse-members aline with each other and form an approximately continuous and unbroken roof-supporting surface; in combination with unit-tying members secured to the right-angled portions of the 95 respective units and, with the base and side-members of a unit, forming a second right-angled triangle, the components of which are all of relatively different length.
5. A building structure including a series 100 of fabricated structural triangular units of identical form, each complete in itself and adapted to be assembled as a roof-supporting series and capable, then, of being disassembled as individual, self-contained units; 105 each of said units comprising a long component to form a base-member, a shorter component to form a side-member, and a component of greater length than the base-member to form a hypotenuse-member, the 110 three components being joined to form a right-angled triangle having a perimeter comprising a single right angle and two acute angles; the series of joined units having their respective acute angles juxtaposed 115 so that the hypotenuse-members aline with each other and form an approximately continuous and unbroken roof-supporting surface; in combination with unit-tying members secured to the right-angled portions of the 120 respective units and, with the base and side-members of a unit, forming a second right-angled triangle, the components of which are all of relatively different length; in combination with a supporting-column 125 comprising a unit in form identical with the aforementioned roof-supporting units and having its hypotenuse-member arranged at an angle to the hypotenuse-members of said units and its long component 130

- disposed in substantial parallelism with the short components thereof and substantially at right angles to their long, base components.
6. A building structure including a series of fabricated structural triangular units of identical form, each complete in itself and adapted to be assembled as a roof-supporting series and capable, then, of being assembled as individual, self-contained units; each of said units comprising a long component to form a base-member, a shorter component to form a side-member, and a component of greater length than the base-member to form a hypotenuse-member, the three components being joined to form a right-angled triangle having a perimeter comprising a single right angle and two acute angles; the series of joined units having their respective acute angles juxtaposed so that the hypotenuse-members aline with each other and form an approximately continuous and unbroken roof-supporting surface; in combination with unit-tying mem-
- bers secured to the right-angled portions of the respective units and, with the base and side-members of a unit, forming a second right-angled triangle, the components of which are all of relatively different length; in combination with two of said units joined together as an apex to the roof and having their respective short components disposed together in vertical parallelism.
7. A roof-truss or similar metal structural frame, including a series of substantially identical right angled triangular frame-units connected together at adjacent corners so that the longer sides of each are arranged in alinement to support a sloping roof-surface, the opposite angles of adjacent units being connected together by tie-members; in combination with supporting-columns joined to the lowermost of the units of the roof-series.

Witness my hand this 27th day of March, 1916, at the city of New York, in the county and State of New York.

JOHN EDWARD JENNINGS.
